UNITED STATES PATENT OFFICE.

CHARLES E. MCBETH, FREDERICK BEUTEL, AND WILLIAM C. MARGEDANT, OF HAMILTON, OHIO.

DESIGN FOR BORING-MACHINES.

Specification forming part of Design No. 5,048, dated June 27, 1871.

To all whom it may concern:

Be it known that we, CHARLES E. MCBETH, FREDERICK BEUTEL, and WILLIAM C. MARGEDANT, of Hamilton, in the county of Butler and State of Ohio, have invented a new and original Design for a Wood-Boring Machine, which is represented in the accompanying photographic illustrations.

We claim as our invention—

The design for a wood-boring machine, as shown.

CHARLES E. MCBETH.
FREDERICK BEUTEL.
WILLIAM C. MARGEDANT.
